UNITED STATES PATENT OFFICE.

ODE D. JENNINGS, OF CHICAGO, ILLINOIS.

COIN-RETURN MECHANISM.

Application filed May 27, 1926. Serial No. 111,987.

This invention relates to coin return mechanisms for vending machines and has for its object to provide a construction more simple and efficient in operation than those heretofore employed.

With these and other objects in view the invention consists in the novel details of construction and arrangements of parts as will be more fully hereinafter disclosed and particularly pointed out in the claims.

Referring to the accompanying drawings forming a part of this specification in which like numerals designate like parts in all the views:

15 Fig. 1 is a rear elevational view of the mechanism as applied to a vending machine;

Fig. 2 is a sectional view taken on the line 2—2 of Fig. 1 and looking in the direction of the arrows;

20 Fig. 3 is a perspective detail view of one of the weights used in conjunction with this apparatus;

Fig. 4 is a perspective view of the merchandise actuated trip controlling the coin return mechanism;

25 Fig. 5 is a sectional view taken on the line 5—5 of Fig. 1 and looking in the direction of the arrows;

Fig. 6 is a view similar to Fig. 5 but showing the parts in a different position;

Fig. 7 is a horizontal sectional view taken on the line 7—7 of Fig. 1 and looking in the direction of the arrows;

Fig. 8 is a view taken on the line 8—8 of 35 Fig. 5 and looking in the direction of the arrows;

Fig. 9 is a horizontal sectional view taken on the line 9—9 of Fig. 1 and looking in the direction of the arrows with parts removed 40 for clearness; and

Fig. 10 is a partial rear elevational view in perspective of the switch mechanism associated with the coin chute.

This invention is an improvement over 45 the construction disclosed in U. S. Letters Patent No. 1,562,771, dated November 24, 1925; in that this invention is directed to a mechanism which will cause a coin to be returned to the operator of the machine 50 after the last article of merchandise has been vended.

In the drawings 1 represents the top plate of the machine adapted to support the coin receiving chute casting generally indicated 55 by the numeral 2 of substantially the same construction as that disclosed in my afore-

mentioned patent. That is to say, the said casting is provided with a chute having an opening 3 for the reception of a coin which normally passes downward past the switch device indicated generally by the numeral 4 to be stopped by the pivoted dog 5, and released therefrom by the pivoted lever 6 all as disclosed in said patent.

Referring to Fig. 5 the parts are shown in their respective positions immediately prior to the release from the magazine 10 of the last article of merchandise 11 therein. The next coin inserted in the chute 3, will pass downwardly therein and permit any suitable mechanism, not shown but well understood, to oscillate the pawl 12 about its shaft 13 so that the tooth 14 thereof will release the star wheel 15 allowing the merchandise 11, through the action of gravity, 75 to pass out of the lower extremity 16 of the magazine 10, and fall into the trough 17 from which it may be obtained by the operator, as clearly shown in Fig. 6. It is to be observed, however, that so long as there are 80 articles of merchandise in the magazine 10, the trip member generally indicated by the numeral 20 will be prevented from entering the magazine 10 under the action of the spring 21, but as soon as the last article of 85 merchandise leaves said magazine, then the said trip device will be oscillated about its supporting shaft 22 so as to project into said magazine.

The trip device 20 particularly illustrated in Fig. 4 is preferably stamped from sheet material and bent to provide the two substantially parallel side members or walls 23 and 24 having the forwardly disposed edges 25 and 26, and upwardly extending 95 ears 28 and 2, each separated by a space 27 from the main body portion of the sides for a purpose presently to appear. The said ears are suitably apertured to receive the shaft 22 upon which the trip member 100 oscillates and the side members are held in spaced relation by a back wall or rear member 30 having integrally formed therewith, or rigidly secured thereto, a tail 31 extending downwardly and away from said 105 wall and whose end is provided with a lateral extension 32 adapted to engage the back edge of the pawl 12.

With particular reference to Figs. 1, 6 and 8 it will be seen that the trip device 20 is so supported by the shaft 22, which in turn is supported by the lugs 35 formed on the rear

side of the magazine supporting plate 36, that the side walls 23 and 24 of said device will lie between the pair of star wheels 15 and extend into the magazine 10 through 5 slotted apertures 37 and 38 respectively.

Likewise secured to the magazine supporting plate 36 are rearwardly extending ears 40 adapted to receive an oscillatory shaft 41 upon which is rigidly secured a weight 10 42 in any suitable manner such as by the screw 43 as particularly illustrated in Fig. 8. The shaft 41 is so disposed that the weight 42 will depend therefrom within the three walls 23, 24 and 30 of the trip device 15 20 so that when said trip device moves forwardly or to the left as seen in Figs. 5 and 6, the rear wall 30 of said device will contact with and swing the weight 42 to oscillate the shaft 41 as indicated from Figs. 5 25 and 6. In this respect it will be understood that, when the trip device 20 is in the position shown in Fig. 5, the weight 42 or such a plurality of them as is required will aid in returning the shaft 41 to its normal inoperative position.

Likewise positively secured to the oscillating shaft 41 to one side of the trip device 20, is a bracket 50 having a depending toe 51 adapted to engage a stop member 52 30 formed on or integrally secured to the magazine supporting plate 36 and of such a length as to determine the amount of oscillation of the shaft 41. The bracket 50 has an arm 53 extending rearwardly to the end 35 of which is pivoted as at 54 one end of a connecting bar 55 whose upper end is pivoted as at 56 to one end of a link 57 centrally pivoted as at 58 to the end of a stationary bracket 59 secured as by the screws 60 to 40 the coin receiving chute casting generally indicated by the numeral 2. A spring 61 disposed between the stationary bracket 59 and the connecting bar 55 exerts an upward pull on said bar thus tending to secure the 45 parts in the position illustrated in Fig. 5, but when the last article of merchandise has left the magazine 10, the trip device 20 will actuate the connecting bar 55 moving the same downwardly or in the direction of 50 the arrow shown in Fig. 5, causing the link 57 to actuate the switch device 4 in a manner that will be readily understood from the drawings. That is to say, and with particular reference to Figs. 1, 5, 6 and 10, it will 55 be observed that when the connecting bar 55 is moved downwardly, the free end 63 of the link 57 will be moved upwardly, contacting with the underside of ear 64 carried by the switch member 4, which will cause 60 said switch member to oscillate about its pivot 65 whereupon the upper and forwardly directed extension 66 of said switch member will enter the aperture 67 in the rear wall of the coin chute casting 2 and lie 65 across the chute 68. The upper surface of

the extension 66 is inclined to the horizontal as clearly shown in Fig. 1 with the result that any coin inserted in the chute subsequently to the delivery of the last article of merchandise from the magazine 10, will 70 not only be obstructed by said extension but, due to the inclined upper surface thereof, will be deflected toward the left as seen in said figure into the auxiliary chute 70 connecting with the chute 71, and returned 75 therethrough to the operator at any convenient point, instead of passing as normally through the regular chute 72 and falling into the coin box 73.

With particular reference to Figs. 5 and 80 6 it will be observed that as the articles of merchandise pass down within the magazine 10, they successively contact with and pass over the forward edges 25 and 26 of the sides 23 and 24 of the trip device 20 and for 85 this reason, the upper extremities of said edges are rounded in order not to stop any of the said articles. Also it will be observed that the spring 21 associated with the trip device 20 will press said edges against said 90 articles of merchandise, and therefore in order that said pressure may never be sufficient to prevent the said articles from being delivered, said pressure is intermittently relieved with each operation of the star 95 wheels 15, or in other words, said pressure is relieved every time an article of merchandise leaves the magazine. This is accomplished through the action of the pawl 12 which, in its rearward movements, will 100 strike the extension 32 on the tail 31 of the trip device 20 and move said trip device rearwardly or away from the magazine 10 so that the articles of merchandise by their 105 own weight may freely pass down said magazine to be successively stopped by the prongs of the star wheels 15 in the usual manner. Thus it will be seen that the articles of merchandise will never be wedged between the trip device 20 and the front 110 wall of the magazine so as to prevent one of said articles being delivered upon the receipt of a coin, especially in view of the fact that ample clearance space is provided in the magazine for said articles, as clearly 115 shown in Fig. 7.

From the foregoing it will be understood therefore that an article of merchandise will be delivered from the mechanism for each coin that is received and retained by 120 the machine, but after the last article of merchandise has left the magazine 10, any subsequently inserted coins will be returned to the operator. This is accomplished by providing the trip member 20 pivoted on 125 the shaft 22 and actuated by the spring 21 which is normally prevented by the article of merchandise from extending into the magazine 10. When the last article of merchandise has left the magazine, however, 130

the said trip device will move into the magazine but in so doing a rear wall 30 thereof will oscillate the weighted shaft 41 and, through the combination of levers 53, 55 and 57, oscillate the pivoted switch member 4 so as to project the upper extension 66, which is normally out of the path of a coin, into and across the coin chute 2 so as to stop the subsequently inserted coins, and the inclined upper surface of said extension will positively deflect said coin into the auxiliary chute 70 for return to the operator. The parts of this mechanism will remain in the position illustrated in Fig. 6 until the particular magazine 10 again receives articles of merchandise, which as will be readily understood will move the trip device 20 rearwardly and thus allow the switch member 4 to assume its normal inoperative position. Due to the disposition of the shafts 22 and 41, it will readily be seen that the spaces 27 formed in the side walls 23 and 24 of the trip device 20 are to receive the shaft 41 and thus allow the trip device 20 to fully function.

It is obvious that those skilled in the art may vary the details of construction as well as the arrangements of parts without departing from the spirit of the invention, therefore, it is not desired to be limited to the foregoing except as may be demanded by the claims.

What is claimed is:—

1. In an apparatus of the class described the combination of a coin receiving chute; means adapted to stop a coin in said chute and deflect the same into a return chute; a magazine for holding a plurality of articles of merchandise adapted to be individually released by a received coin; spring actuated means including a weighted oscillatory shaft serving as a lever and a trip coating with the merchandise in said magazine to actuate said first named means after the release of the last article of merchandise to return said coin.

2. In a coin-controlled vending machine provided with a coin receiving chute and mechanism for delivering an article of merchandise for each coin received, the combination of a magazine for said articles; a switch member carried by said chute and provided with an extension having an inclined surface adapted to enter and cross said chute to intercept and deflect a coin therein, and further provided with an ear; a chute to receive and return the deflected coin to the operator of the machine; means including a plurality of levers and a vertically oscillatable trip coating with said ear and the merchandise in said magazine to actuate said switch member after the release of the last article in said magazine.

3. In an apparatus of the class described the combination of a coin receiving chute; a

magazine for holding a column of articles of merchandise adapted to be individually released by a received coin; a star wheel and detent therefor for controlling the release of said articles; pressure means coacting with said magazine to frictionally engage the lowermost article therein; means carried by said pressure means and actuated by said detent for releasing the pressure on said articles during a delivery thereof; and means actuated by said pressure means for returning a coin inserted in said chute after the release of the last article of merchandise.

4. In an apparatus of the class described the combination of a coin receiving chute; a magazine for holding a column of articles of merchandise adapted to be individually released by a received coin; a star wheel and detent therefor for controlling the release of said articles; vertically oscillatable pressure means coacting with said magazine to frictionally engage the lowermost article therein; means carried by said pressure means and actuated by said detent for releasing the pressure on said articles during a delivery thereof; and means actuated by said pressure means for returning a coin inserted in said chute after the release of the last article of merchandise.

5. In an apparatus of the class described the combination of a coin receiving chute; a magazine for holding a column of articles of merchandise adapted to be individually released by a received coin; a star wheel and detent therefor for controlling the release of said articles; vertically oscillatable pressure means having a plurality of cam surfaces coacting with said magazine to frictionally engage with equalizing pressure the lowermost article therein; means carried by said pressure means and actuated by said detent for releasing the pressure on said articles during a delivery thereof; and means actuated by said pressure means for returning a coin inserted in said chute after the release of the last article of merchandise.

6. In an apparatus of the class described the combination of a coin receiving chute; a magazine for holding a column of articles of merchandise adapted to be individually released by a received coin; a star wheel and detent therefor for controlling the release of said articles; pressure means comprising a U-shaped member coacting with said magazine to frictionally engage the lowermost article therein in a plurality of locations to insure a positive feed of the articles in said magazine; means carried by said pressure means and actuated by said detent for releasing the pressure on said articles during a delivery thereof; and means actuated by said pressure means for returning a coin inserted in said chute after the release of the last article of merchandise.

7. In an apparatus of the class described

the combination of a coin receiving chute; a magazine for holding a column of articles of merchandise adapted to be individually released by a received coin; a star wheel and 5 detent therefor for controlling the release of said articles; pressure means coacting with said magazine to frictionally engage the lowermost article therein; means carried by said pressure means and actuated by said 10 detent for releasing the pressure on said articles during a delivery thereof; and means comprising a system of spring controlled levers actuated by said pressure means for returning a coin inserted in said chute after 15 the release of the last article of merchandise.

8. In an apparatus of the class described the combination of a coin receiving chute; a magazine for holding a column of articles of merchandise adapted to be individually released by a received coin; a star wheel and 20 detent therefor for controlling the release of said articles; pressure means coacting with said magazine to frictionally engage the lowermost article therein; means carried 25 by said pressure means and actuated by said detent for releasing the pressure on said articles during a delivery thereof; and means comprising a system of spring controlled levers and an oscillatory shaft actuated by 30 said pressure means for returning a coin inserted in said chute after the release of the last article of merchandise.

9. In an apparatus of the class described the combination of a coin receiving chute; a 35 magazine for holding a column of articles of merchandise adapted to be individually released by a received coin; a star wheel and detent therefor for controlling the release of said articles; pressure means coact-

ing with said magazine to frictionally engage the lowermost article therein; means carried by said pressure means and actuated by said 40 detent for releasing the pressure on said articles during a delivery thereof; and means comprising a system of spring controlled levers and a weighted oscillatory shaft, serving as a lever, actuated by said 45 pressure means for returning a coin inserted in said chute after the release of the last article of merchandise. 50

10. In an apparatus of the class described the combination of a coin receiving chute; means adapted to stop a coin in said chute and deflect the same into a return chute; a magazine for holding a plurality of articles 55 of merchandise adapted to be individually released by a received coin; and means including a weighted oscillating shaft actuated by a spring controlled trip coacting with 60 said merchandise, to actuate said first named means after the release of the last article of merchandise to return said coin. 65

11. In an apparatus of the class described the combination of a coin receiving chute; means adapted to stop a coin in said chute 70 and deflect the same into a return chute; a magazine for holding a plurality of articles of merchandise adapted to be individually released by a received coin; and means including a system of spring controlled levers and an oscillating shaft actuated by a spring 75 controlled trip coacting with said merchandise, to actuate said first named means after the release of the last article of merchandise to return said coin. 75

In testimony whereof I affix my signature.

ODE D. JENNINGS.
